PEDESTRIAN TRAFFIC SIGNAL

Norman R. Hastings, Huron, S. Dak., assignor to Walk Time, Inc., Huron, S. Dak., a corporation of South Dakota

Application April 15, 1954, Serial No. 30,028

Term of patent 14 years

(Cl. D72—1)

The figure is a perspective view of a pedestrian traffic signal showing my new design.

The sides of the signal not shown are plain.

The essential features of my design reside in those portions shown in full lines.

I claim:

The ornamental design for a pedestrian traffic signal, as shown and described.
